(57) **CLAIM**

The ornamental design for a spiral slicer, as shown and described.

DESCRIPTION

FIG. 1 is a top perspective view of the spiral slicer showing my new design.

FIG. 2 is a side view thereof.

FIG. 3 is another side view thereof.

FIG. 4 is top view thereof.

FIG. 5 is bottom view thereof.

FIG. 6 is a partially exploded top perspective view thereof.

FIG. 7 is another partially exploded top perspective view thereof; and,

FIG. 8 is a fully exploded bottom perspective view thereof. The broken lines in the drawings illustrate portions of the spiral slicer which form no part of the claimed design.
